FIG. 2

FIG. 1

Des. 187,993

PAGE 2

Fig. 1 is a front perspective view of a juvenile vehicle showing my new design;

Fig. 2 is a rear elevational view thereof;

Fig. 3 is a side elevational view thereof; and

Fig. 4 is a top plan view thereof with the pedal and steering wheel portions omitted for convenience of illustration.

The dominant feature of my design resides in the portion shown in full lines.

I claim:

The ornamental design for a juvenile vehicle, substantially as shown and described.
